UNITED STATES PATENT OFFICE.

JOSEPH KOENIG, OF TWO RIVERS, WISCONSIN.

DESIGN FOR A COMB.

SPECIFICATION forming part of Design No. 36,175, dated December 23, 1902.

Application filed January 27, 1902. Serial No. 91,583. Term of patent 7 years.

To all whom it may concern:

Be it known that I, JOSEPH KOENIG, a citizen of the United States, residing at Two Rivers, in the county of Manitowoc and State of Wisconsin, have invented a new, original, and ornamental Design for Combs; and I do hereby declare the following to be a full, clear, and exact description of the same, reference being had to the accompanying drawings, forming a part thereof.

In the said drawings, Figure 1 is a view in side elevation, and Fig. 2 is a vertical sectional view taken on the line 2 2 of Fig. 1, of a comb embodying my new ornamental design.

As shown in the drawings, the leading or material feature of my design consists in raised or relief ornamentation consisting of ornamental scrollwork showing curved lines gracefully combined with irregular-shaped

outlines applied to the comb-back at each end of the face of the same, with a blank space between the ornamentations at said ends, said blank space extending from the teeth to the top of the comb and being of greater length than the length of either of said end ornamentations, the latter being of equal length and completely separated by the said blank space.

Having thus described my invention, what I claim as new, and desire to secure by Letters Patent, is—

The ornamental design for a comb, substantially as herein shown and described.

In testimony whereof I affix my signature in presence of two witnesses.

JOSEPH KOENIG.

Witnesses:

W. J. WRIETH,
G. A. MAGEE.
